UNITED STATES PATENT OFFICE.

PARK A. VAN TASSELL, OF OAKLAND, CALIFORNIA.

MECHANICAL TOY

1,369,504.

Specification of Letters Patent. Patented Feb. 22, 1921.

Application filed June 16, 1919. Serial No. 304,577.

To all whom it may concern:

Be it known that I, PARK A. VAN TASSELL, a citizen of the United States, residing at Oakland, in the county of Alameda and State of California, have invented certain new and useful Improvements in Mechanical Toys, of which the following is a specification.

My invention is a toy parachute.

10 My invention is illustrated in the accompanying drawing which forms a part of this specification and the appended claims.

Referring to the drawing:

Figure 1 is a side view of my toy ready to 15 be shot up in the air.

Fig. 2 is a view of my parachute in the act of descent.

In the drawing, 1 indicates a parachute from which is suspended by cords 2 a weight 20 3 which may be in the form of a man. On one side of the weight 3 near the top thereof is an upturned hook 4 on which hooks the parachute by means of an eye 5 connected to the top of the parachute. On the other 25 side of the weight 3 opposite the hook 4 is a downturned hook 6. To a rod 7 is secured at one end an elastic 8 on the other end of which is secured an eye 9 into which hooks the hook 6.

30 The operation of my invention is as follows:

The rod 7 and the lower part of the para-

chute are grasped and pulled apart, stretching the elastic 8. Upon releasing the parachute the elastic contracts and shoots the 35 parachute up into the air, the hook 6 slipping out of the eye 9. When the parachute has reached the height of the ballistic power of the elastic, the weight 3 drops below the parachute, the hook 4 slipping out of the 40 eye 5, and the parachute opens and descends gradually under the influence of the weight.

Having described my invention, I claim:

1. A toy including a parachute, a weight suspended from the parachute, an upturned hook on said weight, a downturned hook on said weight, an eye on the top of said parachute into which said upturned hook engages, and a projecting device for engaging said downturned hook for projecting the 50 parachute into the atmosphere.

2. A toy including a parachute, a weight suspended from the parachute, an upturned hook on said weight, a downturned hook on said weight, an eye on the top of said parachute into which said upturned hook engages, a rod, an elastic connected at one end to said rod, and an eye connected to the other end of said elastic for engaging said downturned hook.

60 In testimony whereof I affix my signature.

PARK A. VAN TASSELL.
